UNITED STATES PATENT OFFICE.

JAMES F. POWELL, OF FLINT, MICHIGAN; DELBERT J. POWELL ADMINISTRATOR OF
SAID JAMES F. POWELL, DECEASED.

FASTENER.

Application filed May 2, 1927. Serial No. 188,146.

In my Patent No. 1,598,691, dated September 7, 1926, there is disclosed a curtain fastener which may be advantageously used in connection with automobiles for securing one 5 or more curtains to a post carried by an automobile top body, or other structure.

I now aim to improve the post-engaging socket and provide a better construction which is more simple and inexpensive to 10 manufacture, and the construction will be hereinafter specifically described and then claimed. This fastener is particularly characterized by a novel socket, preferably a two-part socket, attached to the curtain or fabric 15 and adapted to receive the post and, so to speak, center it in the socket. Within the socket are post-engaging means which limit the socket to a one-way operation, that is, the socket can only be lifted in one direction 20 from the post and it is by virtue of such post-engaging means that the socket cannot become accidentally displaced.

Reference will now be had to the drawing, wherein

25 Fig. 1 is a vertical sectional view of the fasteners;

Fig. 2 is a rear elevation of the fastener socket;

30 Fig. 3 is a vertical sectional view taken on the line III III of Fig. 1, showing a portion of the socket in front elevation;

Fig. 4 is a vertical sectional view of a fastener illustrating a modified form;

35 Fig. 5 is a rear elevation of the inner member of the socket shown in Fig. 4;

Fig. 6 is a vertical sectional view of the outer member of the socket shown in either Fig. 1 or Fig. 4;

40 Fig. 7 is a detail sectional view showing the manner in which the socket is attached to a curtain or fabric;

Fig. 8 is a vertical sectional view of a fastener illustrating another modified form; and

45 Fig. 9 is a perspective view of an outer member of slightly modified form.

Reference will first be had to Figs. 1, 2, 3, 6 and 7 and the reference numeral 1 denotes a top bow or other support for a post 2 having a head 3 and an annular groove 4. This post 50 is of a conventional form and forms no part of my invention other than a member of the fastener.

The socket in its preferred form comprises 55 an inner member 5 and an outer member 6, said members being substantially oval or

oblong in elevation. The inner member 5 may be, and is here shown as, provided with a plurality of slots 7 to receive malleable tongues or lugs 8 carried by the outer member 6, said lugs extending through a curtain or fabric 9 with the lugs bent on to or clenched against the inner member 5, whereby the curtain will (in the structures illustrated) be sandwiched between the inner and outer members.

60 My preferred form of fastener in its simplest embodiment consists of but two pieces (an inner and an outer member) affixed together so as to grip the curtain or the like sandwiched therebetween. The invention is 65 not, however, confined to this type of fastener for the inner or spring carrying member may be placed adjacent the outer member on the same side of the fabric, and suitably affixed thereto, for example as by prongs or stitching. It will, of course, be clear that, if desired, one or more perforated washers may be interposed between the inner and outer 70 members, or adjacent to and on the opposite side of the curtain, if the inner and outer 75 members be placed adjacent one another.

75 The curtain 9 has a post opening 10 and extending through this post opening into the outer member 6 are resilient portions 11 of the inner member. The resilient portions 11 are formed by providing the inner member 80 with a post opening 12 and radial slits 13 terminating in apertures 14. The slits and apertures are in the upper half of the inner member 85 with one of said slits equi-distant 90 relative to the other slits, so that the upper half of the inner member will be divided and thus provide the similar resilient portions 11. These resilient portions are bent outwardly 95 from the plane of the inner member and extend somewhat into the outer member. The resilient portions 11 terminate to form post engaging edges or lips 15 which are adapted to engage in the groove 4 behind the post head 3.

100 The formation of the post opening 12 in the inner member provides an edge 16, here shown as semi-circular, for engagement with the shank 17 of the post and this edge will bind against the post should an attempt be 105 made to remove the fastener other than the predetermined way.

The outer member 6 has flanged edges 18 that bear against the curtain 9, the material 110 between these flanged edges contributing to

the formation of the prongs or lugs 8. The edges are flanged, both for appearance and for the purpose of presenting a flat surface against the fabric to prevent cutting or shearing of the same when the socket is attached to the fabric. In this way the fabric is preserved and there are no sharp edges to cut it, even though the fasteners be attached by setting tools or machines. The flanged edges 5 in the figures so far mentioned are shown as inturned, but obviously they may be turned outwardly instead, for example, as shown in Fig. 9 hereinafter described. The outer member is the configuration of an inclosure and 10 may be provided with a post receiving opening 19 which receives the head 3 of the post, as shown in Fig. 1. The lower portion of the outer member has a semi-circular wall 20 co-extensive of the lower edge of the post opening 19 and substantially in alignment with the lower edge of the post opening 12 of the inner member. The wall 20 is opposite the 15 resilient portions 11 of the inner member and is sufficiently spaced therefrom to permit the entrance of the socket receiving the post, but only with the resilient portions 11 being somewhat sprung outwardly into the outer member 6 as the socket is forced over the head 3 of the post so that they spring into engagement with the annular neck of the post. The wall 20 here shown and described as 20 semi-circular need not be semi-circular as long as it presents sufficient surface to the stud to aid in holding and centering the stud 25 in the socket and opposes the thrust of the resilient portions.

Greater resiliency may be added to the inner member portions 11 making the same as shown in Figs. 4 and 5. The material between the apertures 14 is bowed, as at 21 to one side of the plane of the inner member and then the resilient portions struck through the post opening 12 at an angle to the axis of said post opening, so that there will be comparatively straight resilient portions terminating at the edges or lips 15. The socket is removed from the post by pulling outwardly on the lower portion of the socket, the wall 20 of the outer member clearing the post head 3 as the lips 15 ride out of the groove 4 of the post. This action might be described as a fulcruming of the engaging edges of the resilient portions on the post as the lower portion of the fastener is swung upwardly and 40 out of engagement with the post. To connect the socket and post, it is simply necessary to place the socket on the post and apply the slight but necessary pressure so that the lips 15 may sufficiently yield until they drop or 45 snap into the annular groove 4 of the post and the socket assumes a closed position relative to the post. It will be noted that the members 50 11 are resilient transversely of their length in order to yield sufficiently to allow the head 55 of the post to push by them for engagement,

but they may be and preferably are substantially rigid or non-resilient to a thrust in the general direction of their length whereby an adverse tip of the post is resisted. Of course the socket as an entirety is comparatively 70 rigid, but there is sufficient flexibility to the curtain or fabric to permit of the socket being flipped off of the post and just as readily returned thereto by insertion of the post plus a slight pressure. 75

As a matter of appearance and finish the outer member of the socket may have an annular raised portion 22 about the post opening 19, which will place the outer face 80 of the socket somewhat flush with the rounded end of the head 3. Anyway there will be no protuberances that might otherwise interfere with the manipulation of the fastener.

Referring to Fig. 8, the modified form of fastener here shown has a wall 20 struck up 85 from the inner member 5 instead of struck down from the outer member 6 as shown in the figures of the drawing heretofore described. The mode of operation is essentially the same in either construction. In some 90 cases it has been found advantageous to make the wall 20 slightly resilient, but this is not essential to a proper working of the device. Fig. 9 as before mentioned illustrates a modified form of outer member having flanged 95 edges 18 bent outwardly instead of inturned and having prongs bent downwardly from the flanged edges 18.

The preferred embodiments of my invention have been illustrated, but it is to be understood that the structural elements are susceptible to such variations and modifications as fall within the scope of the appended claims. 100

What I claim is:—

1. A fastener including a post and socket, said post having a head and an annular groove, said socket having inner and outer members adapted to receive said post, said inner member having a post opening bounded on one side by a resilient portion adapted to engage in the annular groove in said post, said outer member having the configuration of an enclosure extending to said head, the outer member having a wall on the other side of said post opening and in contact with said post adapted to oppose the thrust of said resilient portion on said post. 105

2. A fastener as called for in claim 1, and lugs on said outer member adapted to extend through fabric and said inner member to retain said socket in engagement with the fabric. 110

3. A fastener as called for in claim 1, where-in the resilient portion of the inner member extends into the outer member and has its free edge in engagement with said post whereby it is adapted to fulcrum on said post as the lower portion of said fastener is swung upwardly out of engagement with said post. 115

4. A fastener as called for in claim 1, wherein the resilient portion of the inner member extends into the outer member and is substantially non-resilient to a thrust in the general direction of its length whereby an adverse tip of said post is resisted.

5. A post socket for a curtain comprising inner and outer members adapted to have a curtain sandwiched therebetween, said members having opposed receiving openings adapted to receive a post and the outer member having an additional opening adapted to receive an end of such post, the inner member formed with resilient portions extending in proximity to the additional opening of the outer member, the outer member being formed with a wall opposed to the resilient portions and extending from said additional opening into proximity to the opposed opening of the inner member.

6. A fastener including a post and socket, said post having a head and an annular groove, said socket having inner and outer members adapted to receive said post, said inner member having a post opening bounded on one side by a rigid post-supporting edge and on the opposite side by resilient portions integral with said inner member and adapted to engage in the annular groove in said post, said outer member having the configuration of an inclosure, the outer member having a wall integral therewith opposite said resilient portion and in contact with said post adapted to oppose the thrust of said resilient portions on said post.

7. A fastener including a post and socket, said socket comprising fabric engaging inner and outer members adapted to receive said post, said inner member having a post opening bounded on one side by a curved edge and resilient portions adapted to engage in an annular groove in said post, said outer member having the configuration of an inclosure provided with a post opening and a wall adapted to oppose the thrust of the resilient portions of said inner member.

8. A fastener including a post and socket, said post having a head and an annular groove, said socket having inner and outer members adapted to receive said post, said inner member having a post opening bounded on one side by resilient portions adapted to

engage in the annular groove in said post, said outer member having the configuration of an inclosure provided with flanged edges, the outer member having a wall on the other side of said post opening and in contact with said post adapted to oppose the thrust of said resilient portions on said post.

9. A fastener including a post and socket, said post having a head and an annular groove, said socket, having inner and outer members adapted to receive said post, said inner member having a post opening bounded on one side by integral resilient portions adapted to engage in the annular groove in said post, said outer member having the configuration of an inclosure provided with a post opening and flanged prong carrying edges the outer member having a wall on the other side of said post opening and in contact with said post adapted to oppose the thrust of said resilient portions on said post.

10. A fastener including a post and socket, said post having a head and an annular groove, said socket having inner and outer members adapted to receive said post, said inner member having a post opening bounded on one side by resilient portions engaging in the annular groove in said post, said outer member having the configuration of an enclosure over a considerable portion of said post and provided with a post opening, the outer member having a wall on the other side of said post opening and in contact with said post adapted to oppose the thrust of said resilient portions on said post.

11. A fastener including a post and socket, said post having a head and an annular groove, said socket having inner and outer members adapted to receive said post, said inner member having a post opening bounded on one side by resilient portions integral with said inner member engaging in the annular groove in said post, said outer members having the configuration of an inclosure extending to said head and provided with a post opening, the outer member having a wall integral therewith on the other side of said post opening and in contact with said post adapted to oppose the thrust of said resilient portions on said post.

In testimony whereof I affix my signature.

JAMES F. POWELL.
